ELECTRIC CONTROLLED TIMING DEVICE

Harrison H. Fogwell and Charles H. Judd, Los Angeles, Calif.

Application August 25, 1928. Serial No. 302,106

8 Claims. (Cl. 161—1)

This invention relates to a timing device as applied to the circuit of an electric motor, by means of which the motor may be cut in and out of operation intermittently and without supervision.

The objects of the invention are; first, to provide a simple and effective timing mechanism for an electric circuit; second, to so combine the elements that the movements of the timing mechanism shall control the circuit of the electric motor of a pump; third, to provide a means whereby the operations of the motor shall be intermittent and variable as to time intervals; and fourth, to eliminate all personal supervision.

Heretofore, oil well operators have experienced difficulties in the operation of their pumps, in that many wells do not have sufficient flow to allow of continuous pumping, but must be pumped dry, then allowed to refill and then pumped again. It was found that if the pump were operated intermittently at one hour intervals, or for an hour and then rested for two hours, or for whatever periods of operation and rest the particular well in question might demand, the production of the well was materially increased. Because such intermittent control involved considerable attention and reliance on the unreliable human element, the automatic control herein disclosed was adopted.

Though the invention relates primarily to the operation of pumps for wells, it is to be understood that the principle may be used in many other relations, and it is intended that the claims herein made shall not be limited to said primary purpose any further than their specific language renders such limitation necessary.

The invention is illustrated in the accompanying drawings, in which,

Fig. 1 is a front elevation of the entire mechanism, the cover of the cabinet being removed; Fig. 2 is a sectional view taken on the line 2—2 of Fig. 1; Fig. 3 is a sectional view taken on line 3—3 of Fig. 1; Fig. 4 is a sectional view of the timing mechanism taken generally on line 4—4 of Fig. 1; Fig. 5 is a diagrammatic view of the electric circuits employed, and Fig. 6 is a fragmentary view of a modification of parts of the timing mechanism.

Referring first to Fig. 5, M indicates an electric motor. While this motor may be used for other purposes, its primary use is for driving a pump for an oil well W. The motor is in what may be termed the main circuit, the conductors of which are shown at a and b. This is usually a high voltage circuit. It is opened and closed automatically at predetermined time intervals by a switch

which is operated by a timing mechanism in an auxiliary controlling circuit, the leads of which are shown at c and d. This auxiliary circuit is preferably of a relatively low voltage.

In Fig. 1 of the drawings, A is a suitable casing enclosing the operating parts of the device, and 1 is the usual electric switch of the low voltage, auxiliary circuit, c and d. When the switch is turned on, it throws a current through the fuse 2 and the wire 3 to the terminal 4 of the clock mechanism, which is indicated generally at 5. From the terminal 4, the current passes through the arbor 6 and the hour hand 7, on which are two wiping contacts 8 and 9 which pass, in their orbits, over concentric rows of apertures 10 and 11 in the dial 12 of the clock, which dial is made of suitable insulating material.

Within the apertures 10 and 11, and counter-sunk below the face of the dial, are metallic inserts forming contacts points 13 and 14, respectively which connect at their lower ends with metallic rings 15 and 16, said rings being set within the lower or inner side of the dial 12, whereby they are insulated from the clock mechanism and from each other. The hand contacts 8 and 9, which are of spring material, bear upon the dial face except when they reach their respective apertures 10 and 11 when they snap into position to engage with their respective dial contact points.

Thus, when the hand contact 8 snaps into any of the apertures 10 containing a dial contact point 13, an electrical connection is established to the ring 15, and the current passes from said ring, through a wire 17, to a leaf spring contact 18. Similarly, when the hand contact 9 snaps into any one of its apertures 11, it establishes connection, through its respective dial contact point 14, with the ring 16 and, through a conductor 19, to another leaf spring contact 20.

As will be noted from Figs. 1 and 5, the apertures 10 and 11 in the dial are in staggered arrangement so that the hand contacts 8 and 9 reach them at different times and in alternation. At no time will both hand contacts close with their dial contact points 13 and 14 simultaneously. The apertures will be spaced about the dial so as to give the desired time intervals to the closures of the circuit through the leaf spring contact 18 and 20. As shown in Fig. 1, the time interval is one-half hour. Exactly on the hour, the contacts 9 and 14 close; then at the half-hour, the contacts 8 and 13 close. As indicated in Fig. 5, the apertures 10 and 11 may be closely spaced so as to provide for short time intervals. The dial contact points 13 and 14 are preferably 110

in the form of short machine-screws which are threaded into holes in the respective rings 15 and 16. This makes it possible to remove the dial contacts, and to rearrange or readjust them so as to give any desired time intervals. As will be understood, the apertures 10 and 11 may be placed in radial line on the dial and not staggered, as hereinbefore described, in which case the alternate engagement of the hand contacts with their respective dial contacts can be secured by making one of the dial contacts longer than the other, as is indicated in Fig. 6 of the drawings.

When electrical connections are established, as described, from the hour hand 7 to the leaf spring contact 18, the current in the auxiliary circuit passes thereto to a contact point 21 and a wire 22 to an electromagnet 23. Being thus energized, the latter draws down its armature 24, the carrying member 24a of which is pivoted to a pin 25. In its movement, the armature carries with it an arm 26, said arm also being pivoted on the pin 25 and held yieldingly in this position with respect to the member 24a by a spring 27 which surrounds the pin 25 and the arm 26. By means of a nut 28a on the lower end of the spring 27 may be regulated. Rigidly secured to the arm 26 is a transverse member 29 of insulating material, to which are rigidly secured spring contacts 30, which are respectively connected across the member 29 by insulated conductor 31. Thus, when the armature 24 and the arm 26 are drawn down by the magnet 23, the spring contacts 30 are correspondingly moved until they engage contact points 32, when the main circuit is closed to start the motor M. As will be clear from Fig. 3, the spring contacts 30 are relatively long so as to be resilient, being placed somewhat under stress when they are in closed position.

It is noted at 33 is a detent member 34, which serves at its free end a catch 35, said catch being so positioned as to engage a hooked finger 36 on the armature carrier 24a, when the armature is drawn down by the magnet 23, thereby holding the contacts 30 closed and under stress. Set within the member 34 is an armature 37. When the armature 37 is attracted by its magnet 23, a leg 38, which is rigidly secured to the arm 26, is in such position as to hold the contact spring 20 from its contact point 39, and the leaf spring contact 18 is allowed thereby to connect with its contact point 21. When the armature 37 is attracted by its magnet 23, these positions being attained, the leaf spring 18 is moved by the magnet 23 out of contact with the point 21, and the leaf spring contact 20 is allowed to close against its contact point 39. However, no current can flow through the auxiliary circuit until a connection is established between the hour hand 7 and the metallic ring 16 by the hand contact 9 entering into an aperture 11 containing a dial contact point 14. When this occurs, the current flows, as previously described, through the leaf spring 20 and the contact point 39, over the wire 22 to an electromagnet 41. Being thus energized, said magnet attracts its armature 37, attracting the detent member 34 and releasing the hooked finger 36 from the catch 35. The increased pressure of the spring contacts 30, the magnet 23 and the leaf spring contact 18 causes the arm 26 to snap outwardly, thus separating the spring contacts 30 and their contact points 32, and so breaking the main line to the motor, which causes it to stop. Simultaneously, the leg 38 forces the leaf spring 20 away from its contact

39. No current will flow through the magnet 23, however, until connection is again made through the clock mechanism 5, in the manner described.

From the above it will be seen that when the parts are in the position indicated in Fig. 2 with the main switch closed, four springs are under stress. Two of these are the contacts 30, one is the leaf-spring 18, and the other is the coiled spring 27 on the pin 25. Some time before the magnet 41 is energized to release the hooked finger 26, the current has ceased to flow through the magnet 23 and there is no pull on the armature 24 and its carrying member 24a. When, therefore, the magnet 41 is energized and the catch 35 is lifted, the three spring contacts, 30, 30 and 18, act simultaneously to swing the frame 26 and leg 38 in a clockwise direction to open the main switch and to force the leaf-spring 20 from its contact 32. At the same time, the spring 27 expands and swings the carrier frame 24a and the armature back into contact with the frame 26 which it strikes with a hammer-like blow, thus to assure that the main circuit will be opened at the contacts 32 and the auxiliary circuit to the leaf-spring 20 will be opened at the contact 39.

To prevent any possible short circuiting and arcing, walls of insulating material 42 and 43 are set up on each side of the spring contacts 30. A base 44 of insulating material serves to insulate all the operating parts of the mechanism from the case A.

Until the hand contact 9 is again brought into engagement with another dial contact point 14, set in one of the apertures 10, the motor will not operate; and once operating, it will not stop until the hand contact 9 closes upon a dial contact point 14 in one of the apertures 11. Since these apertures may be located at any desired points, and the metallic inserts forming the dial contact points may be shifted as desired, it will be seen that any frequency of intermissions may be secured.

By the relatively simple circuits and mechanisms thus described, the stated objects of our invention are satisfactorily attained.

Having thus disclosed our invention and the manner in which the same is operated, what we claim as new and desire to secure by Letters Patent is:

1. In an electric system, the combination of a main circuit, a switch in said circuit, an auxiliary circuit, a pair of electromagnets in parallel arrangement in said auxiliary circuit, an armature for one of said electromagnets, a carrier for said armature, a pivoted leg connected with said carrier and rocked as the armature is moved, a pair of spring contacts in the circuits leading to said electromagnets, said spring contacts being on opposite sides of the said leg so as to be operated by the latter in opposite directions as the said leg is rocked, switch members connected with the said leg and forming the movable parts of the switch in the main circuit, said members being operated to close the main circuit when the said armature is attracted, means for temporarily holding the said switch members in their closed positions, and means under control of the other electromagnet for releasing the said switch members and breaking the main circuit, the said leg and the cooperating spring contacts being so arranged that, upon the movement of the said armature carrier in either direction, the leg moves one spring contact away from its co-operating contact point and permits the other

- spring contact to engage with its cooperating contact point.
2. In an electric system, the combination of a main circuit, a switch in said circuit, an auxiliary circuit, a pair of electromagnets in parallel arrangement in said auxiliary circuit, an armature for one of said electromagnets, a pivoted carrier for said armature, a pivoted leg yieldingly connected with said carrier and rocked with the latter as the armature is moved, a pair of spring contacts in the circuits leading to said electromagnets, said spring contacts being on opposite sides of the said leg so as to be operated by the latter in opposite directions as the said leg is rocked, resilient switch members yieldingly connected with the armature carrier and forming the movable parts of the switch in the main circuit, said members being operated to close the main circuit when the said armature is attracted, means for temporarily holding the switch members under stress in their closed positions, and means under control of the other electromagnet for releasing the said switch members and breaking the main circuit, the said leg and the cooperating spring contacts being so arranged that, upon the movement of the said armature carrier in either direction the leg moves one spring contact away from its cooperating contact point and permits the other spring contact to engage with its cooperating contact point.
3. An electric system comprising a main circuit of high voltage having normally open contacts therein, an auxiliary circuit of low voltage having branches in parallel arrangement, an electro-magnet in one of the branches of said auxiliary circuit, an armature for said electro-magnet, a frame, connections between the armature and said frame, means operable by said frame when the electro-magnet is energized for closing the contacts in the main circuit, a latch for holding the said means in closed position, a second electro-magnet in another branch of the auxiliary circuit for releasing the latch to break the main circuit, and means under control of the said frame for causing the said electro-magnets to be energized in alternation.
4. An electric system comprising a main circuit of high voltage having normally open contacts therein, an auxiliary circuit having branches in parallel arrangement, an electro-magnet in one of the branches of said auxiliary circuit, a pivoted armature for said electro-magnet, a frame pivoted coaxially with the said armature, connections between said armature and frame through which the latter is moved in one direction by the armature, means carried by said frame for closing the contacts in the main circuit when the magnet is energized, a latch for holding the frame in position for maintaining the contacts closed, a second electro-magnet in another branch of the auxiliary circuit for unlatching the said frame and permitting the closing means thereon to open the said contacts, and means under control of the said frame for switching the current in the auxiliary circuit from one electro-magnet to the other in alternation.
5. An electric system comprising a main circuit of high voltage having normally open contacts therein, a switch for controlling said circuit, an auxiliary circuit of low voltage having branches in parallel arrangement, an electromagnet in one of the branches of said auxiliary circuit, a pivoted armature for said electro-magnet, a pivoted frame, said frame carrying the said
- switch whereby when the said electro-magnet is energized the switch is closed, resilient connections between the said frame and armature, a latch for holding the switch in its closed position with the said resilient connections under stress, a second electro-magnet in another branch of the auxiliary circuit for unlatching the switch to cause the latter to break the main circuit, and means under control of the said pivoted frame for causing the said electro-magnets to be energized in alternation.
6. An electric system comprising a main circuit of high voltage, a switch for controlling said circuit, an auxiliary circuit of low voltage having branches in parallel arrangement, an electro-magnet in one of the branches of said auxiliary circuit, a pivoted armature for said electro-magnet, a frame pivoted coaxially with the said armature, said frame carrying the said switch whereby when the said electro-magnet is energized the switch is closed, resilient connections between the said frame and armature, a latch for holding the armature in its closed position with the said resilient connections under stress, a second electro-magnet in another branch of the auxiliary circuit for unlatching the armature to cause the switch to break the main circuit, and means under control of the said pivoted frame for causing the said electro-magnets to be energized in alternation.
7. An electric system comprising a main circuit of high voltage having normally open contacts therein, an auxiliary circuit of low voltage having branches in parallel arrangement, an electro-magnet in one of the branches of said auxiliary circuit, a pivoted armature for said electro-magnet, a frame connected with and movable with said armature when the electro-magnet is energized, electrically connected spring contacts carried by said frame and adapted to close against and connect the contacts of the main circuit when the electro-magnet is energized and the said frame is moved, a latch for holding the armature and the spring contacts in their closed positions, a second electro-magnet in another branch of the auxiliary circuit for unlatching the armature and for causing the spring contacts to break the main circuit, and means under control of the said frame for causing the said electro-magnets to be energized in alternation.
8. An electric system comprising a main circuit of high voltage having spaced contacts therein, an auxiliary circuit of low voltage having branches in parallel arrangement, an electro-magnet in one of the branches of said auxiliary circuit, a pivoted armature for said electro-magnet, a frame pivoted coaxially with said armature, resilient connections between the frame and armature, electrically connected spring contacts carried by said frame and adapted to close against and connect the spaced contacts of the main circuit when the electro-magnet is energized and the said frame is moved, a latch for holding the armature and the spring contacts in their moved position with the said resilient connections under stress, a second electro-magnet in another branch of the auxiliary circuit for unlatching the armature and for causing the spring contacts to break the main circuit, and means under control of the said frame for causing the said electro-magnets to be energized in alternation.

HARRISON H. FOGWELL.
